UNITED STATES PATENT OFFICE.

HANS K. LORENTZEN, OF NEW YORK, N. Y.

COIN-CONTROLLED VENDING MACHINE.

Application filed July 25, 1923. Serial No. 853,653.

This invention relates to an improved and simplified construction of coin-controlled vending machines.

It is an object of the invention to provide a vending device particularly adapted to handle cylindrical packets or containers and to insure the invariable delivery of a packet or return of the coin with every effort to operate the machine following the insertion 10 of a coin of the proper denomination in the coin receiving slot.

The invention includes the provision of an indicator including a rotatable pointer capable of being actuated by a knob to indicate which one of a series of varieties of the material being vended is desired. The turning of the knob to actuate the indicator also rotates, through a flexible chain connection, the shaft of a push rod that forms 20 a common actuator for the release mechanism of all the article storage ways comprised in the vending device. The rotation of the push button shaft angularly adjusts an arm carried by the shaft in such relation to one of a series of release gate actuating rods that the subsequent operation of 25 the push rod through the turning of a knob forming part of the coin receiving mechanism, actuates the releasing device of the particular storage chamber pointed out by the indicator.

The invention also includes a special construction of article releasing gate which includes a pair of arcuate jaw-like members 35 whose opposite edges are movable to and from each other to permit an article to enter the space enclosed by the arcuate members and then to drop therefrom upon its final release.

Other features of the invention will be hereinafter referred to.

In the drawings in which a preferred form of the invention has been selected for illustration,

Figure 1 is a view in transverse vertical section of a vending device embodying the invention.

Figure 2 is a horizontal section on the line 2-2 of Figure 1.

Figure 3 is a plan view on an enlarged scale of a detail of article releasing mechanism and the operating means therefor.

Figure 4 is a view in front elevation of the mechanism shown in Figure 3.

Figure 5 is a view in vertical section of the mechanism shown in Figure 3.

Figure 6 is a view similar to Figure 5 taken at another point.

Figure 6^a is a sectional view of a detail.

Figure 7 is a view in rear elevation of the 60 coin receiving mechanism contained in the device shown in Figure 3.

Figure 8 is a view in end elevation of the releasing mechanism shown in Figure 3.

Figure 9 is a view in disassembled relation of the casing and a rear cover plate therefor.

Figure 10 is a view similar to Figure 5 showing the relation of parts that prevent operation of the dispensing means when the 70 articles to be dispensed are exhausted.

Figure 11 is an isometric view of a modified form of dispensing device embodying the invention.

Figure 12 is a view in rear elevation of the 75 device with the rear cover plate removed.

Figure 13 is a view similar to Figure 12 of a cover plate for the device shown in Figure 12.

Figure 14, is a view of the internal construction of coin directing mechanism forming part of the device.

Figure 15 is a view similar to Figure 14 but taken from the reverse side and showing parts operated by a coin.

Figure 16 is a detail view on an enlarged scale of parts of the construction shown in Figure 15.

Figure 17 is a view in vertical section taken at right angles to the views shown 90 in Figures 14 and 15.

Figure 18 is a view similar to Figure 15 but taken from a point farther to the left as seen in Figure 17.

Figure 19 is a detail of gate operating 95 means.

Referring to the drawings for a more detailed description of the invention, a casing 10 having a removable back cover plate 11 is adapted to receive the dispensing device 100 which includes a plurality of vertically extending storage spaces or ways 12. The storage ways 12 are arranged in two groups on opposite sides of the central portion of the casing and arranged one behind the 105 other as is clearly shown in Figure 2 of the drawing. Each of the storage ways 12 is provided at its lowermost extremity with a releasing gate or shutter 13 formed of two arcuate jaws 14 adapted to be rotated about 110 a common center to bring either their upper or their lower edges into separated or adja-

cent relation to perform an article-releasing operation.

An actuating means common to all the releasing devices 13 takes the form of a rotatable arm 15 carried by a shaft 16 and adapted to have its angular position varied so as to be brought into confronting engagement with the adjacent end of one or other of a series of longitudinally slidable push rods 17, each of which has a direct operative engagement with one or other of the releasing devices referred to.

In order to actuate the shaft 16 and thereby in turn actuate one of the push rods 17, a bell-crank lever 18 is pivoted at a point 19 and is provided with an arm 20 extending in operative engagement with a collar 21 fixed on the shaft 16. It will be seen that with this construction a movement to the right in Figure 3 of the drawing of the arm 22 of the bell-crank lever 18 will have the effect of moving the arm 20 in a direction to cause the arm 15 on the shaft 16 to engage and operate one or other of the release mechanism actuating push rods 17.

At 23 is shown a suitable coin receiving device which includes a disk 24 having a cut-out segment 25 adapted to receive a coin such as 26 which may be inserted in the coin receiving device through a suitable slot 27. The disk 24 is carried on a common shaft with a turn knob 28 which can be grasped by a user and turned in a clockwise direction to carry the coin 26 past a suitable pawl member 29 which prevents the return of the coin once it has passed that point. The following movement of the coin causes it to engage an arm 30 pivoted at a point 30' and to swing this arm to the left as viewed in Figure 7 of the drawing. The arm 30 thereupon engages the arm 22 already referred to as forming part of the bell-crank 18 and produces the movement of one of the push rods 17 that is required to operate one or other of the releasing devices 13 as has already been pointed out.

The coin holding pawl 29 which has been referred to forms part of an arm 31 which is engaged at its opposite end by a laterally extending spring arm 32 carried by a lever 33 which is held in a coin engaging position by the spring 34. The lever 33 is provided at 35 with a coin engaging cam portion which lifts the lever 33 and thereby swings the pawl 29 into position to prevent a washer from operating the machine. By reversing the knob the washer is caused to reissue through the slot 72. When the coin has traveled far enough to pass the cam portion 35 of the lever 33 the cam is pushed into position back of the coin by the spring 34 and the pawl 29 is thereupon released as will be clear.

In order to determine which one of the release device actuating rods 17 is to be

operated, a knob 36 is provided accessible to an operator and connected through a flexible chain drive 37 with a sprocket 38 carried by the shaft 16 already referred to. The shaft on which the knob 36 is mounted is also provided with a sprocket 39 connected through a chain drive 40 with a similar sprocket 41 which is mounted on a shaft 42 carrying an indicating pointer 43. The pointer 43 is adapted to be moved over a scale having designations thereon which refer to the different article storage ways 12 and thereby enable the operator to select which one of the storage ways he desires to receive an article from. It will be seen that the rotation of the knob 36 to bring the pointer 43 to desired position at the same time rotates the arm 15 into operating position with a corresponding release device actuating rod 17. In order to prevent the actuation of the device when the arm 15 stops at a position intermediate the actuating rods 17 a lug or pin 45 carried by the arm 15 is caused to engage the face of a plate 46 through which the rods 17 slide, the pin 45 entering within openings within the plate when the arm is in coincidence with one of the actuating rods 17 and thereby permitting inward movement of the arm 15 as will be seen.

In order to return the arm 15 to its outer position following the operation of one of the releasing devices, a spring 47 is provided which surrounds the rearmost end of the shaft 16 and engages a collar 48 on the shaft 16 and a fixed plate 49 at the rear of the device.

Each one of the actuating rods 17 has a pivoted connection as at 50 with an actuating member 51 pivoted at 52 and carried by the forward arcuate member 14 forming one of the jaws of the corresponding releasing device or gate. The actuating member 51 has a prolongation 53 which engages the forward and lower edge of an actuating device 54 carried by the other arcuate gate member of the pair. It will be seen that with this construction the forward movement of one of the actuating rods 17 under the action of the spring 47 will swing the extended end 53 of the member 51 to the left as shown in Figure 5 of the drawing and lift the extended end 55 of the member 54. This movement of the member 51 in a clockwise direction and the corresponding counter-clockwise movement of the member 54 serves to swing the lowermost edges of the arcuate jaw members 14 into relatively adjacent or closed position to thereby prevent an article 56 received between the jaws from being released from that position in which it is held by the jaws until an inward movement of the corresponding actuating rod 17 has taken place.

Upon the inward or rearward movement 130

of the actuating rod 17 the actuating member 51 is swung about the pivot 52 in a counter-clockwise direction. At the same time a projection 57 carried by the member 51 engages the upper edge of the extremity 55 of the member 54 and swings the member 54 in a clockwise direction. It will be seen that a corresponding movement is given to the arcuate gate members 14, that is, the upper edges of the gate members are brought into relatively close adjacency such that an article cannot pass between their edges, while at the same time the lower edges of the arcuate members are spread apart allowing the article 56 that had been contained between the members to fall out or be released. It will be seen that the immediately following forward movement of the actuating rod 17 under the action of the spring 47 again closes the lower edges of the arcuate members 14 and opens the upper edges thereby permitting the next article to fall into position between the gate members.

In order to prevent the actuation of the gate member when the last article has been exhausted from its storage way, a rectangular block 60 is placed in each storage way immediately above the uppermost article therein so that when the last article has been discharged from the way the block 60 will descend into position between the gate members 14 and prevent the bringing together of the upper edges of the gate members thereby preventing the inward movement of the corresponding actuating rod 17 as well as preventing the operation of the coin receiving device or trap door. The result is that the device not having been operated, the coin will fall forward of the trap door and be returned to the would-be purchaser or operator on the article delivery shelf 67.

In order to return the coin to the operator in the event that the knob 28 has been turned so far as to prevent its reverse rotation, a coin deflecting plate 61 is pivoted at 62 and connected through a link 63 with an arm 64 carried by the shaft 16. By this arrangement the inward or rearward movement of the shaft 16 produces a corresponding pull on the link 63 and swings the plate 61 from the position shown in Figure 6 of the drawing to a position in which the coin discharged upon the upper part of the plate will be deflected to the left to an extent sufficient to cause the coin to enter a coin box 65 suitably placed to receive the same. In the event that the link 63 has not been actuated the coin will fall forwardly of the plate or trap door 61 and descend through an opening 66 to the delivery shelf 67 at the lowermost and forward part of the casing which houses the device. The delivery shelf 67 also serves to receive the articles which, for the purpose of the invention, are cylindrical members 68 and fall from the gate members 13 to the

sloping surface 68 and through the passage 69 to the sloping base 70 of the casing; thence they roll to the delivery shelf 67 as will be seen.

Referring to Figure 1 and Figure 2 of the drawing, it will be seen that the releasing devices 13 are arranged in both a horizontally and a vertically stepped arrangement to facilitate the operation of the various devices through the grouped actuating rods 17. To assist in the closing of the gate members following a releasing operation, spring members 72 are provided as is shown in Figure 8 of the drawing which are attached to arms 73 fixed to the shafts of the forward gate member in each releasing device. It will be seen that the pull of the spring 72 rotates the gate members 14 to their receiving position.

In order to prevent breakage of the apparatus when a storage way has been emptied and the gate thereof blocked against operation the collar member 21 may slide on the shaft 16 against the yielding pressure of the relatively stiff spring 74 thereby permitting the shaft 16 to remain unmoved.

In the form of the invention shown in Figures 11 to 19 inclusive a single storage way 70 is provided and the gateway thereof is directly operated by the manipulation of a knob 71 following the insertion of a coin in the slot 72. The coin operated mechanism in this form of the invention includes parts similar to those already described.

A disk 73 carried by the shaft of the knob 71 has a cut-out sector adapted to receive a coin and to press the edge of the coin against the arm 74 in the rotation of the disk. The arm 74 is engaged by the hooked end of the short arm of a bell crank lever 75 whose longer arm extends through a slot in a vertically movable link member 76 connected to an arm 77 carried by one of the gate members. It will be seen that movement of the arm 74 to the right as viewed in Figure 15 will lift the long arm of the lever 75 and rock the arm 77 of the gate as seen in Figure 19. The arm is connected through a pin and slot device 78 with an arm 79 attached to the other gate member so that the gate members are operated in unison as will be clear.

A link member 80 connects the gate operating arm 79 to a crank arm 81 adapted to engage a lug 82 or a coin deflecting member 83 so that the upper part of the deflecting member can be swung to the right to rest in the depression 84 in Figure 17 of the drawings. In this position of the deflecting member a coin dropping from the notch in the disk 73 engages the deflecting member 83 and is diverted into the coin box 85. In the event that a coin is rotated with the disk without accompanying operation of the gate, which has been blocked following the delivery of the last article, the deflecting mem-

ber is not swung to the right and the coin drops through the casing into the delivery tray 67.

In Figure 14 of the drawings is shown an arm 86 pivoted at 87 and adapted to be lifted by a cam member 88 on the knob shaft against the pull of a spring 89. A second arm 90 pivoted at 92 is connected to the arm 86 through the coil spring 91. The arm 90 is caused to swing to the left when the arm 86 is lifted to overlap the deflecting member or coin trap door 83 and hold it in deflecting position during the rotation of the knob and after the gate members have moved to closed position. It will be seen that the engagement of the lug 82 with the crank arm 81 forms a one-way operating connection that provides for this function. In the event that, for any reason the arm 90 engages the edge of the plate 83 the spring 89 will yield and prevent breakage of the parts.

A further safeguard against breakage is provided in the operating engagement between the bell crank 75 and the link 76. This consists of a vertical slot in the link 76 in which the arm 75 may rise against the tension of the spring 91 when the gate members are blocked.

What I claim is:—

30 1. In an article dispensing device, a plurality of vertically extending article storage spaces, an article support for each of said article storage spaces normally supporting the articles therein and movable to constitute a releasing device at the lowermost extremity of each storage space for releasing one article therefrom at a time, a push rod actuating member for each device, the ends of the push rods remote from the devices being arranged in an arcuate disposition, and a master push rod having an arm angularly adjustable for cooperative relation with any of said push rods for actuation of the corresponding releasing device.

45 2. In an article dispensing device, a plurality of vertically extending article storage ways, an article support for each of said article storage spaces normally supporting the articles therein and movable to constitute a releasing device at the lowermost extremity of each storage space for releasing one article therefrom at a time, a push rod actuating member for each device, the ends of the push rods remote from the devices being arranged in an arcuate disposition, a master push rod having an arm angularly adjustable for cooperative relation with any of said push rods for actuation of the corresponding releasing device, and means for rotating the master push rod to select the release actuating member to be operated.

60 3. In an article dispensing device, a plurality of vertically extending article storage ways, an article support for each of said article storage spaces normally supporting

the articles therein and movable to constitute a releasing device at the lowermost extremity of each storage way for releasing one article therefrom at a time, a push rod actuating member for each device, the ends of the push rods remote from the devices being arranged in an arcuate disposition, a master push rod having an arm angularly adjustable for cooperative relation with any of said push rods for actuation of the corresponding releasing device, a rotatable pointer movable over a scale having designations representing the different storage ways, and a sprocket and chain connection between the indicator and the master push rod for adjusting the arm to correspond to the position of the indicator.

4. In an article dispensing device, a plurality of vertically extending article storage ways, an article support for each of said article storage spaces normally supporting the articles therein and movable to constitute a releasing device at the lowermost extremity of each storage way for releasing one article therefrom at a time, a push rod actuating member for each device, the ends of the push rods remote from the devices being arranged in an arcuate disposition, a master push rod having an arm angularly adjustable for cooperative relation with any of said push rods for actuation of the corresponding releasing device, means for rotating the master push rod to thereby adjust the position of the arm to operate the desired releasing device, and means for actuating the master push rod to operate the releasing device.

5. In an article dispensing device, a plurality of vertically extending article storage ways, an article support, for each of said article storage spaces normally supporting the articles therein and movable to constitute a releasing device at the lowermost extremity of each storage way for releasing one article therefrom at a time, a push rod actuating member for each device, the ends of the push rods remote from the devices being arranged in an arcuate disposition, a master push rod having an arm angularly adjustable for cooperative relation with any of said push rods for actuation of the corresponding releasing device, a rotatable pointer movable over a scale having designations representing the different storage ways, a sprocket and chain connection between the indicator and the master push rod for adjusting the arm to correspond to the position of the indicator, and means for actuating the master push rod to operate the releasing device.

6. In an article dispensing device, an article releasing member including a pair of arc shaped gate members oscillatable in opposite directions about a common axis to move their opposite edges toward or from

- each other, the movement of the gate members to separate their edges at one side of the axis serving to provide an opening through which an article can pass into the space between the members, and the movement of the gate members to provide an opening at the other side of the axis serving to release the contained article while preventing movement of the next adjacent article.
7. In a dispensing device for cylindrical articles, a releasing member including a pair of elongated arc-shaped gate members oscillatable in opposite directions about a common horizontal axis to move their opposite edges toward or from each other, the movement of the gate members to separate their edges above the axis serving to provide an opening through which an article can pass into the space between the members, the movement of the gate members to provide an opening at the lower side of the axis serving to release the contained article while preventing descent of the following article, preventing descent of the following article, actuating members at the end of said gate members for operating one of the gate mem-
- bers when the other actuating member is operated, and means for operating one of said gate actuating members.
8. In a dispensing device for cylindrical articles, a releasing member including a pair of elongated arc-shaped gate members oscillatable in opposite directions about a common horizontal axis to move their opposite edges toward or from each other, the movement of the gate members to separate their edges above the axis serving to provide an opening through which an article can pass into the space between the members, the movement of the gate members to provide an opening at the lower side of the axis serving to release the contained article while preventing descent of the next adjacent article, and a follower member adapted to be placed on top of the tier of articles and to enter the gate and prevent the operation of same when the last article has been released.

In testimony whereof I affix my signature.

HANS K. LORENTZEN.
